UNITED STATES PATENT OFFICE

2,043,048

LADLE

Charles E. Lehr, Bethlehem, Pa., assignor to
Bethlehem Steel Company, a corporation of
Pennsylvania

Application December 15, 1934, Serial No. 757,600

7 Claims. (Cl. 22—81)

This invention relates to hot metal ladles and, more particularly to a rolled steel all-welded construction which reduces the weight over previous cast designs.

5 I construct my ladle shell of three rolled plates. Two plates form the side shell, and another plate forms the bottom. The bottom plate is flat and reinforced with bars to prevent distortion of the plate and to provide a flat base for 10 the ladle to rest upon if necessary during an emergency, and also to provide a flat surface for the refractory lining. The spacing of the reinforcing bars is made to suit standard brick shapes so as to reduce chipping and facilitate 15 laying. The spaces between the bars are filled with standard fire brick to the tops of the bars, and a protective layer of standard brick is laid over the top of the bars so as to entirely cover the bottom.

20 Rolled steel trunnion blocks are welded to the ladle shell, and trunnions welded to the blocks and to the shell.

A system of reinforcing ribs radiating from the trunnion blocks distribute the stresses due 25 to lifting the filled ladle.

A flat bottom is more desirable than a dished bottom because of the disadvantage of the dished bottom when setting the ladle down except on 30 a ladle stand, due to tipping out of plumb for lining, heating, etc.

One of the objects of the present invention is to provide a ladle of maximum carrying capacity with the least amount of dead weight in the ladle.

35 Another object is to construct the ladle of rolled material in a manner requiring the least amount of welding, and thereby reduce its cost.

A further object is to provide an improved trunnion structure of economical design and to 40 provide reinforcing members welded thereto for distributing the lifting load.

A still further object is to provide a flat bottom for the ladle, and reinforcing for the bottom so as to prevent distortion due to the weight 45 of the metal carried by the ladle, and to effect a stable base for the ladle when resting on the ground.

The novel features will be more fully understood from the following description and claims taken with the drawings.

50 Fig. 1 is a plan view of the ladle with a portion of the top rim plate omitted;

Fig. 2 is a view in end elevation partly in section;

55 Fig. 3 is a side elevation view;

Fig. 4 is a sectional view taken on lines 4—4 of Fig. 3;

Fig. 5 shows a trunnion pin;

Fig. 6 shows the manner in which the trunnion is welded to the trunnion block; 5

Fig. 7 is a transverse sectional view taken through the top edge of the ladle;

Fig. 8 is a sectional view through the trunnion taken on lines 8—8 of Fig. 3;

Fig. 9 is a transverse sectional view taken 10 through the bottom corner of the ladle; and,

Fig. 10 shows a modification of Fig. 9.

Referring more particularly to Figs. 1, 2 and 3 of the drawings, there is illustrated a tapering ladle shell of elliptical section comprising two 15 curved side plates 10 and 11 and a light bottom plate 12. The two side plates being welded together along their longitudinal edges 13 and 14, and the bottom plate is welded to the inside 20 surface of the side plates as shown by welds 15 in Figs. 9 and 10.

On top of the bottom plate, Figs. 1 and 9, is shown reinforcing bars 16 extending across the narrow dimension of the ladle. These bars are welded at their ends to the inside of the 25 shell plates, and at their bottom edges 18 to the bottom plate so as to directly transmit the vertical load on the bottom plate to the side plates and to prevent it from being distorted.

Between the bars 16, I weld short longitudinal 30 members 19 and 20, and around the pouring spout hole 21 I form a box by means of members 22, all welded together to form a unitary network of beams for the suspension of the bottom plate 15, whereby the bottom load is transmitted 35 through the bars to the side plates 10 and 11 in a vertical shearing manner and without tendency to contract or expand the bottom of the ladle and thus throw additional stress into the vertical 40 welds of the side plates.

With a light bottom plate reinforced in this manner, distortion thereof and radial contraction is prevented, thereby relieving the shell 45 plates of contracting forces such as occur in an unreinforced bottom whether it be flat or outwardly dished.

Fig. 9 shows the preferred form for constructing the bottom because no hot metal capacity is sacrificed such as would occur were the reinforcing bars placed under the bottom plate as shown 50 in Fig. 10. Furthermore, with the bottom constructed as shown in Fig. 9, a smooth flat bottom is provided which is advantageous when setting the ladle on a ground floor. A bottom constructed 55 in this manner will not cut into the ground and

tip as would happen were the reinforcing bars placed underneath. Again, a reinforced flat bottom will not be distorted when set on ground which is not perfectly flat. Obviously, a ladle having a reinforced flat bottom has several advantages over the ladle having a flat or dished bottom and constructed in the usual manner.

Fig. 7 shows a top reinforcing plate 23 in overlapping relation to the top perimeter of side plate 11. The top plate is doubly welded at points 24 to the side plate at its inside and outside edges. This plate not only reinforces the top of the ladle but also protects the brickwork. The dot and dash lines 25 indicate the brick lining. Plate 23 is reinforced with gussets 26 welded thereto and to the inner surface of the shell plates. This construction provides an unusually strong and laterally stiff reinforcement for the rim and with a saving in weight over ordinary practices having equal physical characteristics.

In Fig. 9 the bottom lining comprises bricks 27 set on edge between the ribs 16. The spacing between the ribs is sufficient to allow the use of standard bricks with a minimum amount of chipping. A top layer of bricks 28 covers the tops of bars 16. These bricks are laid flat.

The construction of the bottom lining as shown in Fig. 10 is generally similar to that shown in Fig. 9, the only practical difference between these two constructions resides in the positioning of the ribs 16.

With reference to Figs. 3, 4, 5, 6 and 8, the trunnion housing comprises a flat trunnion block 29, preferably square, welded to the outside of the ladle shell as indicated at 30. The block is bored for receiving the trunnion 31, and around the inner edge of the bore is cut a welding chamfer 32 so that the block may be welded to the shell plates not only at its outside edges but also at its inner edge, thus providing a double security between the block and the plates.

After the trunnion is inserted into the block it is welded around the chamfered flange 33 to the block as shown in Fig. 6, and its inner edge is welded to the inside of the plating as indicated at 34 in Fig. 8. It will be noted that the trunnion block is chamfered and counterbored for the reception of the trunnion flange 33. This provides an enlarged bearing surface for the trunnion where it enters the block, thereby reducing the tendency of edge cracks to develop around the outside edge of the hole in the block. The chamfer on the outside edge of the trunnion flange combined with the chamfer of the block forms a groove for the reception of welding material as shown in Fig. 6.

Surrounding the trunnion block are frame-like members comprising a top member 35, a bottom member 36, and two side members 37 and 38. Radiating from the block are similar diagonal members 39, horizontal member 40, and vertical members 41, all welded together and to the shell so as to form a unitary trunnion support free of distorting casting stresses. The bottom members 36 are provided with seating faces 42 for supporting the ladle on a ladle stand.

Circumferential reinforcing rings 43 and 44 merge with frame members 35 and 36 respectively. These rings are welded to the trunnion frame members and to the shell plates so as to help distribute the stresses due to lifting the ladle when filled with metal. At spaced intervals gussets 45 are welded to rings 43 and 44 and to the side plates for the purpose of reinforcement.

The ladle is made elliptical not only to increase

its capacity without increasing its height, but also to render unnecessary the difficulty experienced in bending thick plates to a circle at or near their edges and to provide flat surfaces for the application of the trunnion blocks, thus obviating forming and fitting the blocks to tapering curved surfaces.

A three part ladle constructed after this manner allows the longitudinal welds for the side plates to be overlapped by the trunnion housings, thereby providing additional ties between the edges of the plates.

Various modifications obviously may be made in the details of the foregoing construction without departing from the spirit of the invention as embodied in the appended claims.

Having thus described my invention, what I claim as new and desire to secure by Letters Patent, is:

1. In a ladle having sides, and a bottom portion reinforced by spaced supporting members secured to the upper side of said bottom and to said sides, the spaces between and the height of said members being substantially equal to the respective length and width of a refractory brick, bricks for filling said spaces, and an additional course of brick laid over said members and said space filling bricks.

2. In an elliptically shaped ladle, a body portion formed of two curved plates having their end portions in abutting relation and welded together, a bottom for the ladle, and trunnion housings mounted over said joints and welded to said plates so as to reinforce said joints.

3. In an elliptically shaped ladle, a body portion formed of two curved plates having flat end portions in abutting relation and welded together to form the body, a bottom for the ladle, a flat trunnion block mounted upon the flat surface of the plates formed by said end portions, said block and plates being provided with an opening for the reception of a trunnion, said block being welded around its outside and around the inside edge of said opening to the side plates.

4. In a ladle for molten metal having a metallic shell provided with an opening for receiving a trunnion, a trunnion block having a trunnion orifice aligned with said opening, the corner defining the edge of said orifice being chamfered adjacent the opening in said shell, welding material placed in said chamfer for securing said block to said shell, welding material applied around the outside of said block for securing the block to said shell, a trunnion mounted in the orifice of said block and projecting through the opening in said shell, and means for holding the trunnion in place.

5. In a ladle for molten metal having a metallic shell provided with an opening for receiving a trunnion, a trunnion block having a trunnion orifice aligned with said opening, the corners defining both edges of said orifice being chamfered with the outside chamfer being further counterbored, welding material applied to the chamfer of the block adjacent the shell and welding material applied around the outside of the block for doubly securing the block to the shell, a trunnion pin having an end portion adapted to enter said orifice and said opening and a flange adapted to fit said counterbore, said flange being chamfered so as to form a groove between the outside chamfer in the block and the flange, welding material applied to said groove and around the edge of the pin adjacent

the opening in the shell for securing the pin to the block and to the shell.

6. In a ladle for molten metal, a body portion formed of two curved plates having flat end portions in abutting relation and joined together to form the body, a bottom for the ladle, trunnion supports mounted over said joints and welded to said plates so as to reinforce said joints; one of said supports comprising a trunnion block 5 mounted upon the flat surface of the plates formed by said end portions, frame-like members surrounding said block, strut members radiating from said block to the inside surfaces of said frame member; said block, frame and struts being made of separate pieces and welded together to form a unitary support for the trun-

nion free of shrinkage stresses; and body reinforcing rings extending from said frame around the outside of the body, said rings being welded to the frame and to the body for distributing lifting stresses.

7. In a ladle having a side portion formed of plates, means for reinforcing the top perimeter of said side plates comprising a top plate in overlapping relation to the inside and outside top edges of said plates, said top plate being 10 welded to the side plates at the inside and outside top edges of said plates, and gussets welded to the inner surface of the side plates and to the under side of said top plate.
